Primary Examiner — Jennifer L Rempfer*Assistant Examiner* — Bethany Louise Mallino(74) *Attorney, Agent, or Firm* — Griffiths & Seaton
PLLC; JoAnn M. Seaton(57) **CLAIM**

The ornamental design for a hanging graphic display, as shown and described.

DESCRIPTION

FIG. 1 is a top, front perspective view of a hanging graphic display showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In the drawings, the broken lines depict unclaimed subject matter. The long dash-short dash lines indicate the boundaries of the claimed design and otherwise form no part of the claimed design.

1 Claim, 5 Drawing Sheets(56)
